UNITED STATES PATENT OFFICE.

JAMES D. JONES, OF COLUMBIANA, ASSIGNOR OF ONE-THIRD TO FRANK H. TOWNSEND, OF ALLIANCE, OHIO.

WIRE FENCE.

SPECIFICATION forming part of Letters Patent No. 372,625, dated November 1, 1887.

Application filed May 23, 1887. Serial No. 239,124. (No model.)

To all whom it may concern:

Be it known that I, JAMES D. JONES, a citizen of the United States, residing at Columbiana, in the county of Columbiana and State 5 of Ohio, have invented certain new and useful Improvements in Wire Fences; and I do hereby declare the following to be a full, clear, and exact description of the invention, such as will enable others skilled in the art to which it 10 appertains to make and use the same.

My invention relates to wire fences, and has for its object the construction of a fence in which the wires crossing each other may be securely locked against displacement, and 15 may be readily released when it may be desired to separate the fence without injuring any of the parts. As heretofore constructed the wires have been bent at an acute angle to enter the aperture in the clasp, and to 20 afford space for the straight cross-wire to enter between the clasp and the inner surface of the bend in the other wire.

As wire fences are generally made of wire 25 of an inferior quality, in the act of bending so acute an angle as is required with the present form of clasps the wire frequently breaks in the bend, and no provision is made for increasing the clamping-power of the clamp or for releasing the wires by opening the clamp.

30 This invention will be hereinafter described, and particularly pointed out in the claim.

In the accompanying drawings, which form a part of this specification, Figure 1 represents a side elevation of a section of a panel 35 of wire fence. Fig. 2 is an enlarged perspective of my improved clasp, and Fig. 3 is an enlarged side elevation of one clasp applied to cross-wires and showing the reverse side from that shown in Fig. 1.

40 Reference being had to the drawings and the letters marked thereon, A represents a metallic clasp, which, as shown, is of an elliptical concavo-convex figure, with an elongated or elliptical aperture, *a*, formed in it. The 45 ellipticity of the apertures *a* may be increased

and the depth of the aperture *a* may be varied to accommodate wire of greater thickness by bending the clasp more, so as to bring the sides *b c* closer together.

B represents the horizontal wires, which 50 may be bent slightly at *d* to enter the elongated aperture *a* in the clasp A and to afford space for the vertical wire C to pass between the clasp and the inner surface of the wire at the point where it is bent.

After the vertical or straight wire has been 55 inserted between the clasp A and the loop or bend in the horizontal wire, the clamping effect of the clasp may be increased by spreading the sides *b c* of the clasp, which will cause 60 the sides of the wall of the elliptical aperture *a* to press upon the straight wire and bind it between the bend or loop in the horizontal wire and the clasp.

The bend *d* of the wire B may be formed 65 after the wire C has been inserted between the wire B and the clasp A by spreading the sides *b c* of the clasp, which will indent the wire B and form a seat for the wire C.

Should it be desired at any time to take the 70 fence apart, this may be readily accomplished without the least injury to either the clasp or the wires by pressing the sides *b c* of the clasp toward each other, which will release the grip upon the wire and permit the straight 75 wire to be easily and readily withdrawn.

It will be observed that by my construction of wire fence only the horizontal wires are bent, and that the bend in them is very slight, which obviates the danger of breaking the 80 wire; that the clasps may be applied to wire of different thicknesses by changing the ellipticity of the aperture in the clasp; that any desired tension may be applied to the clasp, and that the fence may be separated without 85 injuring any of the material.

I am aware that it has heretofore been proposed to construct a fence in which the pickets were provided with recesses to receive the stringers, and rings were placed over the junct- 90

ure of the pickets and the stringers to hold them together and space the pickets. I do not, therefore, claim such a construction.

Having thus fully described my invention,
5 what I claim is—

In a wire fence, flexible plates having an elliptical aperture therein, in combination with horizontal and vertical wires, the longest diameter of the elliptical opening being horizontal, whereby the horizontal wire may be

bent and the vertical wire clamped in the recess by expanding the plate, and the vertical wire released by contracting the same, substantially as described.

In testimony whereof I affix my signature in presence of two witnesses.

JAMES D. JONES.
